C. H. ATKINS.
VACUUM PRODUCER.
APPLICATION FILED DEC. 5, 1910.

1,110,860.

Patented Sept. 15, 1914.

UNITED STATES PATENT OFFICE.

CHARLES HENRY ATKINS, OF SPRINGFIELD, MASSACHUSETTS, ASSIGNOR TO KLEEN-SWEEP MANUFACTURING COMPANY, OF SPRINGFIELD, MASSACHUSETTS.

VACUUM-PRODUCER.

1,110,860.

Specification of Letters Patent. Patented Sept. 15, 1914.

Application filed December 5, 1910. Serial No. 595,592.

To all whom it may concern:

Be it known that I, CHARLES H. ATKINS, a citizen of the United States of America, residing at Springfield, in the county of 5 Hampden and State of Massachusetts, have invented new and useful Improvements in Vacuum-Producers, of which the following is a specification.

My present invention relates to improvements in vacuum producers of the kind or type in which a fluid, as water, that is under pressure, is allowed to escape into a device for producing a rarefaction or lowering of the atmospheric pressure therein. This device is designed to be connected with the floor implement on the one hand and with a suitable discharge device for the waste fluid, as the sewer, on the other.

An important object of the invention is 20 to provide means for overcoming any back pressure that may be exerted at the waste connection.

A further object is to provide means to allow the commingled foreign substances 25 and the waste fluid to flow uninterruptedly into the waste pipe and at the same time to provide means to overcome any back atmospheric pressure at the waste connection.

Broadly, the invention consists of one or 30 more tubular members that are in direct communication with the floor implement, waste pipe, and the escaping fluid from the source of supply, suitable means being also provided to avoid any back pressure to the 35 flow of the fluid to the waste pipe.

In the drawings forming part of this application,—Figure 1 is a view showing the complete system as installed in a building, the vacuum or exhauster device being shown 40 connected to the stand-pipe and the sewer; also the pipe connection leading to the water supply. Fig. 2 is an enlarged vertical sectional view of the vacuum or exhauster device, the section being taken on the line 2—2 45 of Fig. 3, looking in the direction of the arrow and showing the tubular members, the nozzles with their openings arranged in the axis of the tubular members, the head member in which the nozzles are located and 50 to which the tubular members are secured, the pipe connections for source of fluid supply, and the stand-pipe, and the foot member to which the lower ends of the tubular members are connected and the waste-pipe. 55 Fig. 3 is a transverse, sectional view on the

line 3—3 of Fig. 2, looking in the direction of the arrow.

Referring to the drawings in detail, *a* indicates a suitable stand-pipe that is installed in the building, as shown in outline at *b*, 60 which is provided with suitable connections *c* for attaching a hose member, *d*, to which a floor implement *e* is attached. The vacuum producing, or air-exhauster device is designated as a whole by the letter *f* and 65 comprises in detail a head member or piece *g* and a foot member or piece *h*. Located between the head and foot members are a plurality of tubular members *i* which are received in bored out openings *j* and *k*. A 70 rod *m* is provided for connecting the members *g* and *h* together and for holding the tubular members *i* in place. The head member *g* is formed with a cored out portion or 75 fluid chamber *o* with which the supply pipe *p* is connected for furnishing the operating fluid. A suitable shut-off *p*¹ is placed in the pipe *p*. Communicating with the cored-out 80 portion *o* are nozzle elements *q* having conical-shaped openings *r* therethrough; the larger end of the opening being arranged 85 toward the tubular members *i* and preferably in the axis of the same, as clearly shown in Fig. 3. The discharge end of these nozzle elements is spaced from the ends of the 90 tubular members *i*, as shown in Fig. 2 at *s*. This space constitutes a suction chamber and leads to, or communicates with, the stand-pipe *a* to which the floor implement *e* is connected.

The manner in which the water or other fluid under pressure escapes from the conical-shaped openings *r* in the nozzle element *q* is shown by the broken lines *t* in Fig. 2. The foot-member or piece *h* to which the 95 lower ends of the tubular members *i* are connected is formed with a contracted outlet or throat port *h*¹ that is connected to a waste- or sewer-pipe *u*, as shown at *v*. The waste-pipe *u* is provided with the usual trap construction *w*.

In order to overcome and prevent any atmospheric back-pressure, an outlet to the atmosphere is shown at *x*, which outlet opening is in open communication with the 100 waste-pipe *u*; and, as shown, is connected back of the trap *w*. This outlet pipe *x*, as will readily be understood, serves the purpose of permitting the air which has been 105 drawn into the stand-pipe *a* to escape to the 110

atmosphere by reason of the fluid under pressure escaping across the space x , as shown by the arrows y . The air which has been drawn into the stand-pipe could not 5 pass or be forced through the trap w which would render the system inoperative. The commingled water and foreign substances will readily flow by gravity down the waste-pipe and through the trap but the air which 10 has been drawn into the stand-pipe will, as stated, escape through the outlet pipe x .

The operation may be briefly stated as follows: When fluid, under pressure, is permitted to enter the cored-out portion o of 15 the head member g it escapes from the conical-shaped openings r in the manner shown at t and passes into and through the tubular members i . When this fluid flies across the space s a rarefaction of the air in this space 20 occurs and consequently in the stand-pipe a , pipe d , and at the floor implement e , whereby light particles, as dust, lint, etc., are carried, as shown at 3 , across the space s and through the tubular members i to the waste-pipe u . 25

It should be stated, that observation and experiments show the longer the tubular members i , the greater will be the suction effect, or in other words, a higher degree of 30 rarefaction or vacuum effect is produced at the floor implement e . The manner of escape of the air drawn into the stand-pipe to the atmosphere by means of the pipe x , and the carrying away of the foreign substance 35 and water in the waste-pipe u have already been described. The contracted portion h which causes the contents of the tubular members i to come together, assists in drawing the air, water, and foreign substances 40 downward through the members i and into the waste-pipe u .

I have found by experiment that the position of the vacuum producing device f is 45 equally as efficient when placed in other positions than the vertical one. It operates practically as efficiently when placed in substantially a horizontal position, the reason being that the rapid flow of water through the tubular member i is practically inde- 50 pendent of the force of gravity, as can readily be seen by comparing the number of feet a fluid will flow in a second under, say, a pressure of 100 lbs., to the square inch, and the accelerative effect of gravity in the same 55 time, this feature of being able to use the exhauster in almost any position between the horizontal and vertical being an important one since it enables this part of the vacuum cleaner to be more readily installed 60 in places where there would be no room in a vertical one. The exhauster part of my system is, therefore, not limited to a vertical position.

A further important feature of my system 65 is that it is practically independent of the

water pressure. That is to say, it can be installed and successfully used in places where the pressure varies. If the fluid pressure is high then the system will successfully operate with three tubular members. If the water pressure is low more than three tubular members are required, as six or seven. The number of course varies with the water pressure, the object being to obtain the same suction effect at the implement e , or in other words to move the same volume of air.

The system is also applicable for the purposes of ventilation and cooling dwellings. The air that escapes from the pipe x is not only free from any dust but has become 80 cooled by being in contact with the water in the tubular members i , and when it escapes from the pipe x will purify and cool the surrounding atmosphere. It will therefore be seen that I have devised a vacuum cleaner 85 system and an air exhauster device for use therewith that is very efficient and one that can be operated at a small expense.

It will also be observed that the construction herein described involves an enlarged 90 suction chamber having a large and capacious inlet in open communication with the standpipe, in combination with an outlet having an open vent, all of which provides 95 means for carrying a large volume of air, and producing a moderate vacuum, these being necessary essentials in a vacuum cleaning system.

What I claim, is:—

1. In a vacuum producer, the combination 100 with a standpipe having connections for the floor implement, of an exhausting device comprising an upper header member provided with an enlarged suction chamber having a large and capacious inlet in open communication with the standpipe, a fluid chamber in communication with a source of water supply under pressure, and a jet nozzle arranged to jet the water across the suction chamber, a lower header member in open communication with the suction chamber of the upper header member, and an outlet connection with the lower header member, said outlet connection having an open vent. 105

2. In a vacuum producer, the combination 115 with the stand-pipe having connections for the floor implement, of an exhausting device comprising upper and lower hollow header members and a plurality of discharging tubes connecting the opposite headers and in 120 communication therewith, the lower header also having a single member in communication with a waste pipe connection, and the upper header also having a suction chamber in open communication with the stand-pipe 125 and with the upper ends of said tubes, said upper header member also having a fluid chamber in communication with a source of water supply under pressure and provided with jet nozzles having conical openings and 130

lying in axial alinement with the upper ends of the tubes and arranged to jet the water across the suction chamber into the tubes.

3. In a vacuum producer, the combination 5 with a standpipe having connections for the floor implement, of an exhausting device including a header member in communication with a source of water supply under pressure and provided with an enlarged suction 10 chamber having a capacious inlet in open communication with the standpipe, an out-

let connection having an open vent, a pipe with parallel walls therein providing communication between the suction chamber and said outlet connection, and means for passing a jet of water directly across the capacious suction chamber and into the said pipe. 15
